United States Patent Office

Des. 183,925
Patented Nov. 18, 1958

183,925

CARD COLLATOR

Walter Furlani, Endicott, and Myron F. Davis, Jr., Binghamton, N. Y., assignors to International Business Machines Corporation, New York, N. Y., a corporation of New York

Application December 9, 1957, Serial No. 48,834

Term of patent 14 years

(Cl. D26—5)

FIG. 1.

FIG. 2.

Fig. 1 is a perspective view of a card collator, embodying our design.

Fig. 2 is a rear perspective view of the same.

The dominant features of our design reside in those portions shown in full lines on the drawings.

We claim:

The ornamental design for a card collator, as shown and described.
